UNITED STATES PATENT OFFICE.

WILLIAM E. RIECKEN, OF GLENDALE, NEW YORK, ASSIGNOR TO WESTERN ELECTRIC COMPANY, INCORPORATED, OF NEW YORK, N. Y., A CORPORATION OF NEW YORK.

CONNECTING PLUG.

Application filed April 26, 1918. Serial No. 230,874.

To all whom it may concern:

Be it known that I, WILLIAM E. RIECKEN, a citizen of the United States, residing at Glendale, in the county of Queens, State of New York, have invented certain new and useful Improvements in Connecting Plugs, of which the following is a full, clear, concise, and exact description.

This invention relates to connecting plugs and particularly to a connecting plug adapted to be used as the terminal of a telephone cord and to cooperate with a telephone jack.

It is usual in connecting plugs of the class referred to, to provide in addition to the contact making portions, a handle portion which is utilized in inserting a plug into a jack and it is also common to provide the handle portion with an insulating sleeve.

It has, heretofore, been the general practice to utilize the insulating sleeve also as a cover for a recess of the body portion of the plug in which recess is provided the terminals for the electrical conductors which are associated with the plug. In order to permit access to these connections, it has been the practice to make the insulating sleeve removable and to secure it in place by means of a small screw passing through an aperture of the insulating sleeve.

It has also been proposed to employ other fastening means for this purpose, such as, for example, a spring pressed pin carried by the plug and adapted to engage the insulating sleeve. However, as the body portion of the plug is necessarily limited in size, and space is necessary for the mounting of binding screws to prevent the attaching of electrical conductors to the plug, it is desirable to provide a fastening device, the operating parts of which occupy little space and which does not interfere with the binding screws or conductors associated with the plug.

In order to attain this desirable result in accordance with a feature of the invention, the space or clearance between the walls of the aperture usually provided for the introduction of electrical conductors therein and the conductors, is utilized to provide a space for the spring actuating member by the fastening device.

More specifically in accordance with this feature of the invention, the fastening device takes the form of a spring-pressed member or pin passing through a wall of the plug and the insulating sleeve surrounding

such wall, which member is actuated by means of a substantially semi-circular spring engaging the inner walls of the body portion of the plug so that the conductors may be passed to attaching points or binding screws 60 within the plug without in any way interfering with the spring-pressed member or with its spring.

These and other features of the invention, not specifically mentioned above, will more 65 fully appear from the annexed specification and the accompanying drawing, in which Fig. 1 is a plan view of the plug with the insulating sleeve shown in section; Fig. 2 is a vertical section through the plug and sleeve; 70 and Fig. 3 is a detail view in perspective showing the mounting of the spring-pressed member of the invention.

The plug of the invention is of the two-conductor type, that is, it provides for the 75 extension to suitable contacts of the jack of two conductors. The plug consists of a body portion indicated at 1 and a projecting portion or stem indicated at 2, which projecting portion is adapted to be inserted in 80 a suitable jack. The projecting portion 2 is provided with a longitudinal bore in which is inserted an insulating sleeve 3 which projects beyond the portion 2 and which in turn provides a seat for the conducting rod 85 4 which is oppositely screw-threaded on opposite ends. Secured to the outer end of the rod 4 is the tip conducting piece 5 which is separated from a dead sleeve 6 by means of an insulating washer 7. The dead sleeve 6 90 is also similarly electrically separated from the portion 2 by means of an insulating washer 8. On the other end of the rod 4 are secured the terminals 10 and 11 which are separated by an insulating piece 9 and 95 which are secured in position by means of a nut 12. Suitable binding screws 13 and 14 are threaded into apertures in the terminals 10 and 11. Secured to the body portion of the plug by means of the screw 17 is the 100 strain relieving piece 15.

As shown more clearly in Figs. 2 and 3, the body portion of the plug is provided with substantially cylindrical ends which are separated by a rectangular cut-out section. The rear end of the body portion of the plug, however, takes the form of a ring or annulus through which the conductors of a cord 16 together with a strain relieving strand are led to the terminals 13 and 14 and 110

- the strain relieving piece 15 respectively. Adapted to surround the cylindrical walls of the body portion of the plug is the sleeve of insulating material 18. This sleeve is 5 provided with an aperture indicated at 19 in which a pin 20 is adapted to be thrust by means of a substantially semi-circular spring member indicated at 21 when the sleeve is slipped over the body portion of the 10 plug. This spring member is provided on its ends with lugs 22 which engage the edges of the annulus 23 so as to be guided thereby and to also retain the spring in position. It will be observed that inasmuch as the 15 spring member 21 conforms closely to the inner walls of the ring 23, it does not interfere in any way with the conductors which pass through such ring to the terminals of the plug.
- 20 In order to remove the sleeve from the plug to obtain access thereto, it is merely necessary to use a pointed instrument, such as a pencil or the equivalent to depress the member 20 against the force of the spring 25 21, thus bringing the ends of the spring 21 together. The sleeve may then be slid off the plug, since when the member 20 is once depressed, the inner surface of the sleeve will maintain it in depressed position until 30 the sleeve is removed.

What is claimed is:

1. A connecting plug comprising a body

portion, a removable sleeve for said body portion, and a retaining means for said sleeve including a substantially semi-circular member of resilient material, a pin operated thereby adapted to engage said sleeve and means confining the ends of said resilient member causing said member to press against said pin.

2. A connecting plug comprising a body portion, having an annular portion, a removable sleeve therefor, retaining means for said sleeve comprising a retaining member arranged to engage said sleeve, a resilient actuating member therefor confined within said annular portion and conforming to the inner surface thereof, and means for retaining said actuated member within said annular portion.

3. A connecting plug comprising a body portion, having an annular portion, a removable sleeve therefor, retaining means for said sleeve comprising a retaining member arranged to engage said sleeve, a resilient actuating member therefor confined within said annular portion and conforming to the inner surface thereof, and lugs formed on the ends of said actuating member engaging the edges of said annular portion.

In witness whereof, I hereunto subscribe my name this 23rd day of April A. D., 1918.

WILLIAM E. RIECKEN.
